CLAIM

The ornamental design for a television receiver, as
shown and described.

DESCRIPTION

FIG. 1 is a front and right side perspective view of a television receiver showing our new design;
FIG. 2 is a front elevational view thereof;
FIG. 3 is a top plan view thereof;
FIG. 4 is a rear elevational view thereof;
FIG. 5 is a left side elevational view thereof;
FIG. 6 is a right side elevational view thereof;
FIG. 7 is a bottom plan view thereof;
FIG. 8 is a cross-sectional view thereof taken on line 8-8' of FIG. 2, with the interior mechanism omitted;
FIG. 9 is a front and right side perspective view thereof with the covers shown open;
FIG. 10 is a cross-sectional view thereof taken on line 10-10' of FIG. 2, with the interior mechanism omitted;
FIG. 11 is a cross-sectional view thereof taken on line 11-11' of FIG. 2, with the interior mechanism omitted;
and
FIG. 12 is a cross-sectional view thereof taken on line 12-12' of FIG. 2, with the interior mechanism omitted.
